UNITED STATES PATENT OFFICE.

NICHOLAS C. THALHEIMER, OF CHICAGO, ILLINOIS, ASSIGNOR TO UNION METAL PRODUCTS COMPANY, OF CHICAGO, ILLINOIS, A CORPORATION OF DELAWARE.

DIAPHRAGM BUFFER MECHANISM.

Application filed December 8, 1924. Serial No. 754,593.

Upper buffer springs are used to keep the diaphragm face plates of adjacent passenger train cars in contact on either a straight or a curved track. Semi-elliptical springs are used for this purpose because they also can be arranged to keep the face plate in the center of the car and also maintain the face plate in its proper angular position. These semi-elliptical springs are rigidly or pivotally attached to the diaphragm face plate at their middle portion and have their extremities attached to the car in such a way as to obtain the above mentioned desired results.

A semi-elliptical spring can be positioned and attached on the outside of the car so that it is noiseless; easy to inspect; accessible for repairs and has a low maintenance cost.

It is common practice to attach the middle of a semi-elliptical spring to the diaphragm face plate and attach its extremities to the end wall of a car with a shackle arrangement having means to restrict the movement of the ends of the spring toward or away from the center of the car. The spring may be reversed and still come within the scope of the invention; that is, the middle of the spring may be attached to the end wall of the car and the extremities of the spring to the diaphragm face plate.

My invention relates to the upper buffer spring mechanism for a diaphragm face plate on a railway passenger train car and resides in the shackle attachment of the extremities of the semi-elliptical spring to the car or to the diaphragm face plate, as the case may be.

Another object is to necessitate a slight compression of the semi-elliptical spring in order to attach it to the shackles.

Another object is to assure an easy movement of the semi-elliptical spring under compression.

Another object is to so arrange the associated parts and restrict the outward movement of the shackle so as to prevent the parts from becoming locked together.

In the drawings:

Fig. 1 is a plan of an upper diaphragm buffer mechanism with my invention applied thereon.

Fig. 2 is a partial front elevation of Fig. 1.

Fig. 3 is a section on line 3—3 of Fig. 2.

Fig. 4 is an enlarged section on line 4—4 of Fig. 1.

Fig. 5 is a detail of the extremity of the spring on line 7—7 of Fig. 3.

In the drawings 1 is the end wall; 2 the diaphragm, and 3 the diaphragm face plate, all of the usual construction. The semi-elliptical spring 4 is attached to the face plate by member 5 and bolt 6 of a pivoted construction may be used to attach the spring to the face plate.

The shackle holder 7 is secured to the car in any desired manner and the shackle 8 is pivoted to the holder 7 by pivot pin 9 and semi-elliptical spring 4 is attached to the shackle 8 by pivot pin 10.

The shackle is provided with stop 23 on one side to restrict or limit the longitudinal movement of the spring toward the center of the car and with stop 24 on the other side to restrict or limit the movement of the spring in the opposite direction.

The normal distance between the extremities 25 of the spring (that is, the centers 26 of the curled ends) is slightly less than the minimum possible distance between the pivots 10 when the shackles are mounted upon the car, so that it is necessary to slightly compress the spring 4 to attach it to the shackles 8. The spring then has a tendency to pull the opposite shackles toward each other and to keep the stop 23 in contact with the car, thus maintaining the associated parts in rigid relation when the car is not coupled to another car. This feature eliminates rattle and noise which is objectionable in a sleeping car. Such a condition would exist when the device is on the rear end of the last car of the train.

It is desirable to have the distance between the opposite outer pivots 10 less than the distance between the opposite inner pivots 9 to assure an easy outward movement of the extremities 25 of the spring when the spring is under compression.

In a construction wherein the spring 4 is attached to the outer ends of the shackles 8 it becomes necessary to restrict the outward swinging movement of the shackles so that the associated parts do not become locked together when the spring is compressed, in which event they could not return to normal position when the pressure is relieved. Such locking would take place when the line of thrust of the spring through the outer pivot (10) passes through the inner pivot (9).

or beyond it; in other words, passed the dead center. The stop 24 prevents such a locking of the parts by restricting the outward swinging movement of the shackle.

5. I claim:

1. The combination with the end wall and diaphragm face plate of a railway car, of shackles pivotally connected at one end to said end wall, a semi-elliptical spring having its middle portion secured to said face plate and having its extremities pivotally connected to the other ends of said shackles, and means to limit the swinging movement of said shackles toward the center of the car, the minimum possible distance between the ends of the shackles to which the spring is attached being greater than the normal distance between the extremities of the spring, whereby the spring must be compressed before it can be attached to the shackles.

2. In combination with the end wall and diaphragm face plate of a railway car, of shackles pivotally connected at one end to one of the aforesaid elements of the car, a semi-elliptical spring having its middle portion attached to the other aforesaid element of the car and having its extremities pivotally connected to the other ends of said shackles, and means to limit the swinging movement of said shackles toward the center of the car, the minimum possible distance between the ends of the shackles to which the spring is attached being greater than the normal distance between the extremities of the spring, whereby the spring must be compressed before it can be attached to the shackles.

3. The combination with the end wall and diaphragm face plate of a railway car; of shackles pivotally connected at their inner ends to said end wall, a semi-elliptical spring having its middle portion engaged with said diaphragm face plate and having its extremities pivotally connected to the outer ends of said shackles, the distance between the pivots at the inner ends of said shackles being less than the distance between the pivots at the outer ends of said shackles.

4. In combination with the end wall and diaphragm face plate of a railway car; of a pair of shackles with their inner ends pivotally attached to said wall and having integrally spaced apart portions, means to re-

strict the swinging movement of said shackles in either direction, and a semi-elliptical spring having its middle portion secured to said face plate with its extremities pivotally connected to the outer ends of said shackles between said portions.

5. In combination with the end wall and diaphragm face plate of a railway car; a pair of shackles with their inner ends pivotally attached to said wall and having integrally spaced apart portions, means to restrict the swinging movement of said shackles in either direction, and a semi-elliptical spring having its middle portion secured to said face plate with its extremities pivotally connected to the outer ends of said shackles between said portions, the minimum possible distance between the outer ends of said shackles being greater than the normal distance between the extremities of the spring.

6. In combination with the end wall and diaphragm face plate of a railway car; of shackles pivotally connected at their inner ends to said end wall, a semi-elliptical spring having its middle portion engaged with said diaphragm face plate and having its extremities pivotally connected to the outer ends of said shackles, and means to restrict the outward movement of said shackles so that the associated parts cannot become locked.

7. In combination with the end wall and diaphragm face plate of a railway car; of shackles pivotally connected at their inner ends to one of the aforesaid elements of the car, a semi-elliptical spring having its middle portion attached to the other aforesaid element of the car, and having its extremities pivotally connected to the outer ends of said shackles, and means to restrict the outward movement of said shackles so that the associated parts cannot become locked.

8. In combination with the end wall and diaphragm face plate of a railway car; of shackles pivotally connected at their inner ends to said end wall, a semi-elliptical spring having its middle portion engaged with said diaphragm face plate and having its extremities pivotally connected to the outer ends of said shackles, and means to restrict the movement of said shackles in either direction.

NICHOLAS C. THALHEIMER.
